UNITED STATES PATENT OFFICE.

PETER R. GONSKY, OF CHICAGO, ILLINOIS.

DESIGN FOR A COMBINATION PHONOGRAPH AND LAMP-STANDARD.

54,984.

Specification for Design.

Patented Apr. 27, 1920.

Application filed June 12, 1919. Serial No. 303,789. Term of patent 14 years.

To all whom it may concern:

Be it known that I, PETER R. GONSKY, subject of the King of England, (declared intention to become a citizen of the United States of America,) residing at Chicago, in the county of Cook and State of Illinois, have invented new, original, and ornamental Design for a Combination Phonograph and Lamp-Standard, of which the following is

a specification, reference being had to the accompanying drawing, forming a part thereof.

The figure is a perspective view of a combination phonograph and lamp standard.

I claim:

The ornamental design for a combination phonograph and lamp standard, as shown.

PETER R. GONSKY.
